UNITED STATES PATENT OFFICE.

GEORGE W. NELSON, OF CLEVELAND, OHIO, ASSIGNOR TO THE STANDARD SEWING MACHINE COMPANY, OF CLEVELAND, OHIO, A CORPORATION OF OHIO.

BOBBIN-CASE LATCH FOR SEWING MACHINES.

Application filed February 15, 1923. Serial No. 619,180.

To all whom it may concern:

Be it known that I, GEORGE W. NELSON, a citizen of the United States, and a resident of Cleveland, in the county of Cuyahoga and State of Ohio, have invented certain new and useful Improvements in Bobbin-Case Latches for Sewing Machines; and I do hereby declare the following to be a full, clear, and exact description of the invention, such as will enable others skilled in the art to which it appertains to make and use the same.

My invention relates to bobbin-case latches for sewing machines, and especially to bobbin-case latches of the type adapted to hold a non-rotary bobbin-case in its operative position within the open chamber of a rotary hook. Some latches of this type, and the kind to which my present invention particularly relates, comprise a pivoted member movable to and from a closed position in front of the hook chamber for holding the bobbin-case therein, and a latch for engaging said bobbin-case holding member and securing it in its closed position. The pivoted holding member when in its closed position should be sufficiently close to the bobbin-case to hold the latter in its seat in the hook chamber but at the same time provide sufficient space between the same for the proper clearance of the needle thread loop when being carried over the face of the bobbin-case by the hook. To provide for such proper positioning of the holding member relative to the face of the bobbin-case in a convenient and accurate way, whereby to adapt it to any variation in the size or position of the parts, or the size of the thread to be used, has been the object of the present invention. To this end, the invention consists in providing an adjustable support for the latch by means of which the position of the latch and associated bobbin-case holder may be adjusted to thereby control the position of the holder relatively to the face of the bobbin-case.

Referring now to the accompanying drawings forming a part of this specification, in which I have shown only so much of a sewing machine as is necessary for the illustration of my invention,

Figure 1 is a front end elevation of a supporting bracket for attachment to the under side of a sewing machine bed-plate, the same carrying a rotary hook with its

contained bobbin-case and my improved bobbin-case holder and latch;

Fig. 2 is a side elevation of the same as viewed from the right in Fig. 1;

Fig. 3 is a top plan view with the hook partly broken away to more clearly show the seating of the bobbin-case therein;

Fig. 4 is a sectional elevation, with the section taken on line 4—4 of Fig. 3, showing the holder and its latch in normal closed position by full lines and in open released position by dotted lines, the rotary hook being omitted;

Figs. 5 and 6 are similar views on an enlarged scale, showing different adjustments of the holder as effected by a shifting of the adjustable fulcrum support for the latch proper, and

Fig. 7 is a section on line 7—7 of Fig. 3, showing the spring-pressed pin for automatically throwing the holder to its open position when released by the latch.

Similar reference characters indicate like parts in the several figures of the drawings.

The hook, bobbin-case, and bobbin-case holder and latch here shown, are the same in a general way as those disclosed in Patent No. 1,274,188, granted to me July 30, 1918.

The hook and associated parts are carried by a bracket 2, adapted to be suitably connected with the bed-plate of the machine, in a manner, for instance, as disclosed in Patent No. 1,228,125, granted to me May 29, 1917.

Journalized in this bracket is a rotary hook shaft 3 carrying at its front end an attached hook 4 having an open chamber in its face side. Removably seated in the chamber of said hook is a bobbin-case 6, which is formed with a peripheral race-bearing surface 7 adapted to be seated in a race-way 8 formed in the said hook chamber adjacent the front side thereof.

The bobbin-case 6 is adapted to be removably retained in its operative position in the open hook chamber by means of a holder located in front of said chamber. This holder is here shown in the form of a cup-shaped disc 9 adapted to substantially cover the face side of the bobbin-case and being attached to a plate 10 having two ears 11, 11, at its opposite sides pivoted to two forwardly projecting arms 12, 12, of the supporting bracket 2, by means of pivot

2
pins 13, 13, whereby the holder may be swung outwardly from the face of the hook to an inclined position, as shown by dotted lines in Fig. 4, permitting of the ready insertion or removal of the bobbin-case and bobbin. When the holder is closed, it is held in such position by means of a latch 14 which is pivotally mounted at one end in an arm 15 of the bracket 2 and has a notch 16 for latching engagement with an adjacent arm 17 of the holder, as shown.

As hereinbefore referred to, the holder 9 should be sufficiently close to the face of the bobbin-case to hold the latter to its seat in the hook but at the same time provide sufficient space between the same for the proper clearance of the needle thread when being carried over the face of the bobbin-case by the hook. As a simple and efficient way of effecting the proper adjustment of this holder relatively to the bobbin-case, I have journaled in the bracket arm 15 a rocker 20 having an eccentric 21 on which the latch 14 is pivotally mounted. Thus by turning the rocker in its bearing, the associated eccentric will likewise be turned and so shift the connected latch either forwardly or backwardly and thereby impart a like movement to the connected holder to adjust its position relatively to the face of the bobbin-case. The manner of effecting such adjustment will be clear by reference to Figs. 5 and 6, which show two different positions of the latch and connected holder 9 relatively to the face of the bobbin-case as effected by a turning of the eccentric pivot for the latch. After the eccentric has been turned to adjust the parts, it is secured in its adjusted position by means of a setscrew 22 threaded into the bracket arm 15 for engagement with the eccentric-carrying rocker 20.

The rocker 20 may be turned by any suitable means to adjust the eccentric 21, the same as here shown being provided with a lever handle 23 at the outer end thereof where it may be conveniently grasped by the operator.

The latch 14 having the notch 16 for latching engagement with the holder arm 17 provides a positive connection between the latch and holder whereby any forward and backward movement given to the latch by an adjustment of its eccentric pivot support will be positively imparted to the holder. While this positive connection between the latch and holder is desirable, it is not necessary for latching purposes, as it will be understood that a single shoulder on the latch for engagement with the holder, such as afforded by the front wall of the notch 16, will be sufficient.

A spring-pressed pin 26 seated in an opening in the front end of one of the bracket arms 12, (see Fig. 7) and normally

pressing outwardly against the pivoted holder, acts to automatically throw the latter to its open position when released by the latch 14. This pin pressing outwardly against the holder also serves to maintain the latter in engagement with the front wall of the notch 16 whereby the holder will be caused to move with the latch during any adjustment of the latter by its eccentric support 21, independently of the engagement of the rear wall of the notch 16 with said holder.

The latch 14 is preferably mounted on its pivot support within a notch 26 in the upper side of the bracket arm whereby it will be so guided in its rocking movements and held against lateral displacement by the side walls of said notch. A spring 27 seated within the notch 26 in the bracket arm and pressing upwardly against the rear end of the latch 14 serves to yieldingly hold the latter in its normal latching position.

The bobbin-case may be held against rotation with the hook during the operation of the machine in any usual or suitable way. As here shown an arm 30 at the upper side of the bobbin-case engages the holder within a notch 31 therein for such purpose.

What I claim is:

1. In a sewing machine, the combination with a rotary hook having an open chamber in its face side, a non-rotary bobbin-case loosely seated in said chamber, and a movable bobbin-case holder, of a pivoted latch for retaining the holder in closed position, and a pivot support for said latch adjustable to shift the latch and thereby control the position of the holder relatively to the bobbin-case.

2. In a sewing machine, the combination with a rotary hook having an open chamber in its face side, a non-rotary bobbin-case loosely seated in said chamber, and a movable bobbin-case holder, of a latch for retaining the holder in closed position, and an eccentric pivot for said latch adjustable to shift the latch and thereby control the position of the holder relatively to the bobbin-case.

3. In a sewing machine, the combination with a rotary hook having an open chamber in its face side, a non-rotary bobbin-case loosely seated in said chamber, and a movable bobbin-case holder, of a latch for retaining the holder in closed position, a rocker mounted in a stationary support and having an eccentric on which said latch is pivoted, and means for turning the rocker and associated eccentric to shift the latch and thereby control the position of the holder relatively to the bobbin-case.

4. In a sewing machine, the combination with a rotary hook having an open chamber in its face side, a non-rotary bobbin-case loosely seated in said chamber, and a mov-

- able bobbin-case holder, of a latch for retaining the holder in closed position, and a rocker mounted in a stationary support and having an eccentric on which the latch is pivoted, said rocker having an operating handle for turning the same and associated eccentric to adjust the position of the connected latch. 5
5. In a sewing machine, the combination with a rotary hook having an open chamber in its face side, a non-rotary bobbin-case loosely seated in said chamber, and a movable bobbin-case holder, of a latch for retaining the holder in closed position, a rocker mounted in a stationary support and having an eccentric on which the latch is pivoted, said rocker having an operating handle for turning the same and associated eccentric to adjust the position of the connected latch, and means for securing the rocker in 10 adjusted position.
6. In a sewing machine, the combination with a rotary hook having an open chamber in its face side, a non-rotary bobbin-case loosely seated in said chamber, and a movable bobbin-case holder, of a latch releasably connected with the holder for retaining the latter in closed position, and an eccentric pivot for the latch adjustable to shift 15
7. In a sewing machine, the combination with a rotary hook having an open chamber in its face side, a non-rotary bobbin-case loosely seated in said chamber, and a pivoted bobbin-case holder, of a pivoted notched latch for connection with the holder to retain the latter in closed position, an eccentric pivot for the latch adjustable to shift said latch and connected holder to regulate the position of the latter relatively to the bobbin-case, and means for securing the eccentric pivot in adjusted position. 20
8. In a sewing machine, the combination with a rotary hook having an open chamber in its face side, a non-rotary bobbin-case loosely seated in said chamber, and a pivoted bobbin-case holder, of a latch movable to and from a position of latching engagement with the holder for retaining the latter in closed position, and a support for said latch adjustable to shift the latch relatively to the holder and thereby control the position of the latter relatively to the bobbin-case. 25

In testimony whereof I affix my signature.
GEORGE W. NELSON.
